UNITED STATES PATENT OFFICE.

WILLIAM T. BOYD AND ELMER E. BOYD, OF ASPINWALL, AND OMER C. KELLER, OF PITTSBURGH, PENNSYLVANIA, ASSIGNORS TO B. B. & B. TRUNK COMPANY, OF PITTSBURGH, PENNSYLVANIA, A CORPORATION OF PENNSYLVANIA.

WARDROBE-TRUNK.

1,185,971.

Specification of Letters Patent.

Patented June 6, 1916.

Application filed April 15, 1914. Serial No. 832,112.

To all whom it may concern:

Be it known that we, WILLIAM T. BOYD and ELMER E. BOYD, residents of Aspinwall, and OMER C. KELLER, a resident of North 5 Side, Pittsburgh, in the county of Allegheny and State of Pennsylvania, citizens of the United States, have invented a new and useful Improvement in Wardrobe-Trunks; and we do hereby declare the following to be a 10 full, clear, and exact description thereof.

Our invention relates to wardrobe trunks.

The invention has for its object to improve these trunks in certain ways by which they will have greater strength, and at the 15 same time retain the clothes in position so as to prevent the jostling of same in the handling of the trunks in transit.

To these ends our invention comprises the novel features hereinafter set forth and 20 claimed.

In the drawings Figure 1 is a perspective view of our improved trunk in open position; Fig. 2 is a vertical section; Fig. 3 is a plan view of one-half the trunk showing the 25 hanger-bracket; Figs. 4 and 5 are details of the hanger-bracket; and Fig. 6 is a perspective view of the retaining-gate.

In the drawing we have illustrated a form 30 of wardrobe-trunk composed of two sections 2 and 3 and hinged as at 4 to swing horizontally. The section 2 contains the drawers or other compartments 5, the top one 5^a having the lid 6 hinged at its inner end as at 7. This compartment 5^a is provided with the 35 cushion 8 which is hinged at the front-end of said compartment as at 9, and when the trunk is opened this cushion or pad rests on the top of said compartment as shown in Fig. 1.

40 The lid 10 of the trunk is recessed on its interior and adapted to cover both sections 2 and 3 when the trunk is closed, as indicated in Fig. 2, and said lid is hinged to the section 2 by suitable hinges, and is held in its raised position by a suitable lock 45 11 as indicated in Fig. 1 which consists of a toggle-like arrangement, the arm 12 having a stud 13 which is adapted to enter the recess 14 in the upper arm so that when the lid is raised the stud 13 will engage the recess 14 and so prevent the lid from falling.

50 The section 3, which may be termed the "swinging-section," as distinguished from the stationary-section 2, is the one which

contains the suits or gowns, and is provided 55 with the hanger-supports 15 upon which the clothes-hangers 16 are adapted to rest. These hanger-supports 15 are carried by the bracket 17 which is raised above the upper end of the swinging-section 3, and said 60 bracket is made up of metal bars, the rear U-shaped bar 18 being secured by screws or other fastening devices 19 to the metal-strip 20 which extends around the upper edge of the section 3. The inner ends of the hanger- 65 supports 15 are secured to the U-shaped bar 18, and the arms 21 at the outer ends of said hanger-supports are secured to the metal-strip 20, said arms being slightly curved inwardly from said strip, as clearly indicated 70 in Fig. 4.

The hanger-supports 15 have the swinging extension 22 which is a U-shaped strap pivoted at 23 to the bar 24 and also to the lug 25 of the metal-strip 20. The clothes-hangers 16 rest on the hanger-supports as indicated in Fig. 1 and when said hanger supports are extended by throwing up the extension 22, the clothes-hangers may be moved along said hanger-support to a point 80 outside the section 3 for convenience in removing or packing the clothes in the trunk. By having the bracket 17 raised in the manner shown above the walls of the swinging-section 3 greater strength is obtained as the 85 bracket is braced and the parts connected together so as to give great rigidity, while at the same time in extending above the walls of the section 3 easier access to the clothes is had, and the clothes-hangers may 90 be lifted and adjusted in place with greater convenience. Locking-fingers 27 are pivoted to the extensions 22 of the hanger-supports and said locking-fingers are adapted to engage the arms 21 so as to hold the extension 95 22 in its raised position.

Within the swinging-section 3 are the notched-bars 28 which are adapted to receive the retaining-gate 29, the projections 30 on the lower end of said retaining-gate being 100 adapted to fit in the notches of the bars 28. The projections 31 at the upper end of the gate have the notches 32 which are adapted to engage the bars 24 of the hanger-supports. By the use of this retaining-gate the 105 clothes may be packed into close contact with each other, so as to hold them against movement when the trunk is being handled,

2

and this gate may be adjusted at different notches in the bars 28 according to the amount of clothing contained within the trunk-section 3. 40

5 When the trunk is packed and ready for closing the cushion or pad 8 is swung over so that said pad rests on the clothes-hangers as indicated in Fig. 2, and when the lid 10 is lowered the inner face of the lid comes in contact with the said pad or cushion, and with sufficient pressure to force said pad down onto the clothes on the hanger and holds the same in position without in any way injuring them or bringing too great pressure to bear thereon. Furthermore, 45 when the lid is closed the inner face of said lid, with the pad interposed, engages the upper end of the gate and, with the lower end of the gate in engagement with the notches 15 28, the said gate is held securely in place. The pad 8 when not in use rests on the lid of the box 5 so that it in no way interferes with the packing operations and furthermore being attached to the lid of the box 5 cannot 50 become lost or misplaced. When the lid is lowered the bracket projects up into the recess of the lid, and in this way space is saved and the height of the trunk reduced, which is very essential, as railroads are charging 55 excess baggage for trunks over a certain height.

What we claim is:

1. A wardrobe trunk comprising two vertically hinged sections; one section forming 35 an open-front clothes compartment, a recessed lid adapted to cover both sections, a bracket on said open-front compartment raised above the upper edges of the walls of said compartment, and an expansible hanger. 60

support carried by said bracket, whereby when said lid is lowered the bracket and hanger support enter said recessed lid. 65

2. A wardrobe-trunk comprising two vertically hinged sections, a hinged cushion attached to one section, clothes hanger-supports on the other section, and said cushion adapted to be swung over onto said clothes hanger-support of the second-section. 70

3. A wardrobe-trunk comprising two vertically hinged sections, one of said sections having a compartment at the upper end thereof, a lid on said compartment, and a cushion hinged to the outer edge of said compartment adapted to be swung over onto the top of the other section. 75

4. A wardrobe-trunk comprising a clothes-compartment, said compartment having notches on both its inner side walls, a retaining-gate with its lower cross bar fitting in said notches, and a hanger-support with 60 which the upper end of said retaining-gate engages. 80

5. A wardrobe-trunk comprising a clothes-compartment, a retaining-gate, engaging means on the inner walls of said compartment engaging the lower end of said gate, and a lid adapted to engage the upper end of said retaining-gate. 85

In testimony whereof, we the said WILLIAM T. BOYD, ELMER E. BOYD and OMER C. KELLER have hereunto set our hands. 90

WILLIAM T. BOYD.
ELMER E. BOYD.
OMER C. KELLER.
